UNITED STATES PATENT OFFICE.

AUGUSTUS JAHANT, OF AKRON, OHIO.

FURNACE FOR HEATING PURPOSES.

SPECIFICATION forming part of Letters Patent No. 441,567, dated November 25, 1890.

Application filed May 10, 1890. Serial No. 351,277. (No model.)

To all whom it may concern:

Be it known that I, AUGUSTUS JAHANT, of Akron, in the county of Summit and State of Ohio, have invented certain new and useful Improvements in Furnaces for Heating Purposes; and I do hereby declare the following to be a full, clear, and exact description of the invention, such as will enable others skilled in the art to which it pertains to make and use the same.

My invention relates to improvements in furnaces for heating purposes; and it consists in certain features of construction and in combination of parts, hereinafter described, and pointed out in the claims.

In the accompanying drawings, Figure 1 is a vertical section through the center of the furnace. Fig. 2 is a front elevation. Fig. 3 is a plan in section on line $x-x$. Fig. 4 is a plan. Fig. 5 is an enlarged detail, in section, of an improved coupling.

A represents the inner wall of the furnace, this furnace being provided with grate A', fire-pot A², combustion-chamber A³, ash-pit a, and doors a' a², all of which may be of ordinary construction.

B is the outer casing inclosing a hot-air chamber B', the latter connecting with the cold-air duct (not shown) leading usually to the outside of the building.

K is a box, preferably of sheet metal, located inside the hot-air chamber B', preferably between the line of doors a' a², this box being adapted to fit and bear against wall A, to which it is secured. An air-duct C extends from outside the furnace through a hole in casing B and discharges into box K. From the two upper corners of the box K lead pipes C' C', these pipes extending up for some distance inside chamber B', as shown, and from thence extend through holes in the furnace, where they connect with extension-pipes C², these latter pipes extending down inside of and close to wall A to or near to the surface of the fuel, and from thence pipes C² turn inward toward the center of the furnace, so that the air-currents discharged from these pipes are directed over the top of the fuel and the two air-currents cross each other approximately at the center of the furnace. Pipes C², being located, as aforesaid, inside the furnace, will eventually burn out and

have to be renewed. Hence these pipes are preferably of cast-iron, and for readily attaching and detaching the same I provide as follows:

Pipes C' are usually of wrought metal and are screw-threaded for connecting with couplings c, each coupling having an external flange c', adapted to bear against the outer side of wall A, the coupling being also provided with a lock-nut c², adapted to engage the inner surface of the wall A. Pipes C² fit easily over the inner ends of coupling c, and are held in place by means of, for instance, pins c³. By withdrawing a pin a pipe C² may be removed and new pipes substituted, the change requiring but a few minutes of time. The outer end of pipe C is provided with a gravity-damper C³, this damper being connected by means of cord or chain D with a similar damper e of smoke-pipe E, chain D engaging suitable sheaves d, the arrangement being such that in closing one damper the other damper is opened. In starting the fire damper C³ is opened wide, and after the fire is under way this damper may be more or less closed to control the fire. After the building has become sufficiently warm, at least in moderate weather, the damper C³ will likely be closed and damper e opened wide, more especially overnight or when the furnace is to be left for several hours without attendance.

In operating the furnace, doors a' a² are kept closed, except as the one door is opened for supplying fuel and the other door is opened for removing ashes. These doors should be well fitted, so that when closed they will admit little or no air. In starting the furnace, the fire-box having been supplied with coal, the kindlers are placed on top of the coal and ignited, and as soon as they are well under way door a' is closed, damper C³ having been previously opened. The heat of the burning kindlers produces a strong current of air through pipes C, box K, and pipes C' C², and as the furnace becomes heated, box K from its contact with the furnace-walls becomes highly heated, and also pipes C', being located inside the hot-air chamber becomes heated to a high degree, by reason of which the air passing through these pipes and box becomes raised to a high tempera-

ture, and hence a hot-air blast is discharged into the furnace. The two currents of hot air, meeting approximately at the center of the furnace and just at or above the surface 5 of the fuel, produce an eddying movement or whirlpool that gathers into its vortex the gases from the fuel, and the commingling of hot air and gases just where the heat is most intense results in a perfect combustion of 10 these elements, and it is found that much better results accrue than with a single current of air admitted for such purpose.

What I claim is—

1. The combination, with a furnace having 15 a fire-pot, a closed combustion-chamber, and a smoke-pipe leading out of the upper end of the latter for the discharge of the products of combustion and having means for excluding air from the grate, of two or more induction air-pipes extending into the combustion-chamber, and adapted to discharge into the furnace at or near the surface of the fuel, and from different points the arrangement of 20 the induction air-pipes being such that the currents of air will cross or engage each other 25

at or near the center of the furnace, substantially as set forth.

2. The combination, with a furnace having an outside casing inclosing a hot-air chamber, of a metal box located in such hot-air chamber, a cold-air duct adapted to discharge into such box, two or more hot-air pipes leading from such box and discharging into the furnace from different points, so that the currents of air will engage or cross each other, 30 a gravity-damper over the cold-air duct, a gravity-damper for closing an air-opening in the smoke-pipe, and a flexible connection between the two dampers, whereby when one damper is opened more or less the other is 35 correspondingly closed, substantially as set forth.

In testimony whereof I sign this specification, in the presence of two witnesses, this 28th day of March, 1890.

AUGUSTUS JAHANT.
